ABSTRACT: The application discloses a space heater into which air is introduced through a static air duct from which it is passed into a combustion chamber having means at its base for imparting rotary turbulence to the air and fuel mixture within the chamber. The hot products of combustion are then caused to pass from the combustion chamber into a radiation heater atop the chamber. Provision is also made to cause the static air rising from the duct to take a separate path into a convection heater section enveloping the combustion chamber. Intermediate the combustion chamber and the radiation heater as a component of the convection heater are deflection means for causing the convection air currents to travel generally outwardly and downwardly in the vicinity of the space heater.

SPACE HEATER

This invention relates to space heaters and, in particular, to such heaters which are portable and have capacity to generate heat by convection and radiation and to uniformly heat objects stationed at any point in its near vicinity.

While it is true in theory that all ambient air heaters causes the temperature to increase by both convection and radiation means, the instant space heater makes special provision for the two modes of heating. This is achieved by providing a special vertical duct serving as a convection heater which receives nonturbulent air from a communicating horizontal duct after sufficient static pressure has been established therein, the rising air in the convection heater being heated by the heater's combustion chamber located proximate thereto. The combustion chamber also receives air from the horizontal duct and separately conveys the heated air and the combustion gases into a radiation section atop the chamber. Means are disposed in the bottom of the chamber for imparting turbulence to the air passing therein for improving the efficiency of combustion. An important feature of the invention is the provision of a deflector to force the convection air currents rising from the vertical duct in the general direction of the floor where it can be used to heat a room space efficiently due to minimizing of heat losses to the upper strata of the air space within the room.

One object of the invention is to provide a new and improved space heater.

Another object of the invention is to provide a space heater which produces uniform and efficient space heating.

A further object of the invention is to provide a space heater which heats by both radiation and forced convection.

Other objects and advantages of the invention may be appreciated on reading the following detailed description of the several embodiments thereof which is taken in accordance with the accompanying drawings, in which:

FIG. 1 is a perspective view of the preferred form of the invention;

FIG. 2 is a section taken on the line 2-2 of FIG. 1;

FIG. 3 is a section taken on the line 3-3 of FIG. 1;

FIG. 3A is a horizontal section taken on the line 3A-3A of FIG. 3;

FIG. 4 is an exploded view of the components forming the combustion, radiation and convection column of the space heater; and

FIG. 5 is a fragmentary view of a modified form of combustion chamber for the space heater.

Referring to the drawings it is seen that space heater is supported on a platform 10 having at one end a handlebar 12 which is an integral extension of a pair of stanchions 14 and supporting legs 16. Proximate the other end are mounted wheels 18 for rendering the heater unit portable.

Air is admitted into the heater through horizontal duct 20 being driven by motor driven fan 22. The duct serves as a static box causing the air to rise into the burner proper at such time as sufficient static pressure has developed in the duct. The rising air then flows along two avenues, one avenue being provided by the cylindrically formed combustion chamber 24, the other avenue being provided by the annular air space between the wall of chamber 24 and vertical duct 26 which envelopes the chamber. The top portion of the vertical duct 26 is formed as a grille 28 at the top of which is horizontal, deflection buffer 30 which causes the air rising through the duct and heated due to its conductive contact with the combustion chamber to pass out through the grille uniformly at a 360° angle being deflected generally outwardly and

downwardly to give even heating by convection to the surrounding atmosphere.

Underneath baseplate 23 of the combustion chamber 24, as shown in FIG. 3A are radial vanes 23a serving to spiral the static air at the top of the duct 20 through aperture 23b and into the combustion chamber 24. The turbulent air in the combustion chamber mixes efficiently for improved combustion therein.

The rotating and turbulent air and fuel mixture that rises up through the combustion chamber 24 is fired by oil burner 25 ignited by electrodes 29. Fuel for the burner is stored in tank 27. The rising gases in the chamber strikes baffle 31 and circulates above the baffle into the infrared heater section 32 consisting of a cylindrical screen member 33, which is perforated and permits the hot combustion gases to exit through the small perforations causing the member 33 to become incandescent and a source of radiant heat. A protective grille 34 surrounding the screen 33 and top cover 35 therefor house the infrared heater serving thereby to protect the users of the space heater from injury during its operation.

Optionally the entire heating column may be lowered into the duct 30, as shown in dotted line in FIG. 3, so that the several sources of heat are lower to the floor whereby heat loss to the upper air strata is minimized.

The space heater shown in the exploded view in FIG. 4 shows the convection and radiation sections of the heater column as separated units for the sake of clarity.

The modified space heater for burning gas shown in the fragmentary view of FIG. 5 provides a venturi tube 40 serving as a mixing chamber disposed over fuel nozzle 42 within horizontal duct 20. The tube communicates with the combustion chamber 24 within which a baffle plate 31 is disposed close to the ignition means 29, the flame in the chamber being confined to the space between the plate and the outlet end of the venturi tube.

I claim:

1. A space heater having an air compartment, a vertically disposed combustion chamber in communication with said compartment, means for introducing and firing a fuel and air mixture in said chamber, a vertical duct in separate communication with said compartment and externally juxtaposed to said chamber whereby the rising air in said vertical duct is in heat transfer relation with said chamber, said vertical duct having an atmosphere communicating outlet therein providing an exit for convection air currents, and a radiation generator mounted atop of and communicating with said combustion chamber.

2. A space heater as defined in claim 1, wherein a convection air current deflector is disposed in said vertical duct.

3. A space heater as defined in claim 1, wherein said air compartment is a horizontal duct and a motor driven fan with its rotating axis horizontally disposed is located at least partially therewithin.

4. A space heater as defined in claim 2, wherein said air compartment is a horizontal duct and a motor-driven fan with its rotating axis horizontally disposed is located at least partially therewithin.

5. A space heater as defined in claim 4, wherein means disposed at the bottom of the combustion chamber are provided for causing the air passing into the combustion chamber to have rotary turbulence whereby the air and fuel mix in the chamber will combust efficiently therein.

6. A space heater as defined in claim 5, wherein said air compartment contains a mixing chamber communicating with said combustion chamber and having a venturi opening adapted to receive a fuel source.
